(57) **CLAIM**

The ornamental design for a portion of a ceiling fan housing, as shown and described.

DESCRIPTION

FIG. 1 is a perspective view from below of a portion of a ceiling fan housing in accordance with my design;

FIG. 2 is a front elevation view of the portion of a ceiling fan housing in accordance with my design; and,

FIG. 3 is a side elevation view of the portion of a ceiling fan housing in accordance with my design, the opposite side being a mirror image of that shown.

The broken lines showing environmental structure are for illustrative purposes and form no part of the claimed design.

1 Claim, 3 Drawing Sheets

UNITED STATES PATENT AND TRADEMARK OFFICE
CERTIFICATE OF CORRECTION

PATENT NO. : Des. 520,634 S
APPLICATION NO. : 29/228038
DATED : May 9, 2006
INVENTOR(S) : Florez

Page 1 of 3

It is certified that error appears in the above-identified patent and that said Letters Patent is hereby corrected as shown below:

The title page showing an illustrative figure(s) 1 should be deleted and substitute therefore the attached title page consisting of Fig(s). 1.

The drawing sheets consisting of Fig(s) 1 should be deleted and substitute therefore the attached drawing sheets consisting of Fig(s) 1.

Signed and Sealed this

Eighteenth Day of September, 2007

A handwritten signature in black ink, appearing to read "Jon W. Dudas". The signature is written in a cursive style with a large, stylized "J" and "W".
